UNITED STATES PATENT OFFICE.

LOUIS WOJIDKOW, OF BROOKLYN, NEW YORK, ASSIGNOR TO NEW YORK STAMPING COMPANY, OF BROOKLYN, NEW YORK, A CORPORATION OF NEW YORK.

VALVE FOR PERCOLATORS AND OTHER APPARATUS.

1,145,641.

Specification of Letters Patent.

Patented July 6, 1915.

Application filed March 26, 1913. Serial No. 757,024.

To all whom it may concern:

Be it known that I, LOUIS WOJIDKOW, a citizen of the United States, residing at Brooklyn, in the county of Kings and State 5 of New York, have invented a certain new and useful Improvement in Valves for Percolators and other Apparatus, of which the following is a full, clear, and exact description.

10 The invention relates to a valve, designed primarily for the percolator tube of a percolator coffee pot, and operating automatically to insure the circulation of the fluid through the tube, although the valve as such 15 is capable of use in shower heads and other articles where an automatically acting valve may be useful.

The invention consists of a valve casing 20 preferably in two parts, the inner part affording means for applying the valve, and the outer part carrying the ported element, the valve itself, in the form of a shell or cup, being supported between these two members in such way as to open and close 25 the ports under variation of pressure, as I will proceed now to explain and finally claim.

In the accompanying drawings illustrating 30 the invention, in the several figures of which like parts are similarly designated, Figure 1 is an elevation, partly broken out, of sufficient of a preferred form of percolator tube to illustrate the invention. Fig. 2 is a longitudinal section, on a larger scale, 35 of a portion of such percolator tube. Fig. 3 is an end view of the valve. Fig. 4 is an elevation of a common form of shower head with the valve of this invention applied and serving as a venting device.

40 1 is a percolator tube and 2 is a plug adapted to fit in a well in the bottom of a coffee pot in such way as to leave but a film of water at the bottom of the well and between such bottom and the bottom of the 45 plug and exposed to the direct heat of the lamp or other heating agent, so that the film of water is flashed into steam and thereby serves to eject the superposed column of water in the tube, and by this action to insure 50 the opening of the valve 3 to admit water from the surrounding vessel, and thus furnish a fresh film of water to be converted into steam to continue the circulation, all substantially in accordance with 55 the invention disclosed in my Patent No.

1,095,973, dated May 5, 1914. A number of valves for use in this connection have been devised, most of which operate by gravity; but my experience is that a valve acting by differences in pressure gives better results 60 than one acting by gravity.

The valve itself comprises an inner member 4, having an outer screwthreaded portion 5, and a tubular portion 6, the outer end of which is provided with a centrally 65 perforated spider or cross-piece 7; and an outer member 8 having a screwthreaded portion 9 by which this outer member is screwed into the inner member 4. This outer member 8 is made with a valve seat 70 10 having the central port 11 crossed by a centrally perforated spider or bar 12. The outer member preferably is provided with a flaring mouth 13.

The valve 14 is a cup-shaped or shell-like 75 structure, of metal, preferably having a central stem 15 projecting at front and rear so as to engage the holes in the spiders 12 and 7 to support the valve and to permit it to respond freely to variations in pressure. 80 As shown this valve cannot close the tubular portion 6 and hence that part is always open for the passage of the fluid, but said valve operates to alternately cover and uncover the valve seat 10 for the circulation 85 of the fluid through the device. In order to insure the non-closing of the part 6, the valve 14 may be provided with any suitable distance piece 15^x, such as a drop of solder used to unite the shell and its stem, or a 90 depression in the shell surrounding the stem.

The valve, as a whole, may be connected to the tube 1 in any suitable manner, as by frictionally engaging a lateral 16 on the tube. 95

By the construction described, the valve itself may be readily detached and disconnected and its parts thus made accessible for cleaning and repair.

The pressure exerted by the conversion of 100 the water into steam will tend to close the valve by driving the shell 14 against the valve seat 10 and closing the port 11 therein, and as soon as this pressure is expended by the expulsion of the superposed column 105 of water from the tube, then the pressure of the externally surrounding water will open the valve and admit water into the tube to be subjected to the heat and converted into steam as before. Thus the valve acts auto- 110

matically under variations in pressure, and is very sensitive. As applied to a shower head, it frequently happens that in these heads when the water is turned off, it will not drain out perfectly, and in that case when the water pressure is removed, the valve will open and admit air into the head and so expel any water that may tend to accumulate in it. As shown in Fig. 4, 17 10 is a shower head of well-known construction, and 18 is a valve such as just described, applied to the shower head and operating as a vent in the manner described.

The inner and outer members of the valve 15 and the shell may be economically made of sheet metal, and standardized for ready renewal of parts. The shell itself is of very light weight and very sensitive to variations in pressure, so that it responds freely to the 20 pulsations of the intermittent expulsions of water through the percolator tube.

Variations in the details of construction are permissible within the scope and spirit of the invention.

25 What I claim is:—

1. A valve, comprising a movable valve member, an inner member provided with an interior tubular portion adapted to engage the article upon which the valve is used and to support it in operative position and serving to limit the inward throw of 30

the movable valve member, an outer member provided with a valve seat and ported for the inward passage of fluid, the movable valve member operating automatically under variations in pressure and co-operating with the said seat to permit and prevent the flow of fluid, and means on the inner and outer members to separably connect them. 35

2. A valve, comprising a movable cup-shaped valve member, an inner member provided with an interior tubular portion adapted to engage the article upon which the valve is used and to support it in operative position and serving to limit the inward throw of the movable valve member, an outer member provided with a valve seat ported for the inward passage of fluid, the movable valve member operating automatically under variations in pressure and co-operating with said seat to open and close the valve, and screwthreaded portions on the inner and outer members to separably connect them. 40

45 In testimony whereof I have hereunto set my hand this 24th day of March, A. D. 1913.

50 LOUIS WOJIDKOW.
